UNITED STATES PATENT OFFICE.

FOSTER W. BASSETT AND WILLIAM A. HUNTER, JR., OF LOS ANGELES, CALIFORNIA.

FLUSHING-VALVE MECHANISM.

957,028.

Specification of Letters Patent.

Patented May 3, 1910.

Application filed June 11, 1909. Serial No. 501,560.

To all whom it may concern:

Be it known that we, FOSTER W. BASSETT and WILLIAM A. HUNTER, Jr., citizens of the United States, residing at Los Angeles, in 5 the county of Los Angeles and State of California, have invented certain new and useful Improvements in Flushing-Valve Mechanism; and we do declare the following to be a full, clear, and exact description of the 10 invention, such as will enable others skilled in the art to which it appertains to make and use the same.

This invention contemplates the construction of an improved flushing valve mechanism 15 provided with means for utilizing the water pressure for controlling the flushing water.

One of the objects of the invention is the production of a flushing valve mechanism 20 provided with means for securing a positive valve action by utilizing the water pressure instead of opposing it.

Another object of the invention is the production of a flushing valve mechanism comprising 25 double valve compartments and a duplex valve united by a lever for controlling said compartments.

Another object of the invention is the production of a flushing valve mechanism comprising 30 a main compartment or chamber controlled by a slide valve and a second or auxiliary compartment or chamber controlled by a ball valve having leverage connections with the first mentioned valve and arranged to coact therewith.

Another object of the invention is the production of a flushing valve mechanism combining the advantages of the gravity and pressure systems.

With the foregoing and other objects in view, the invention consists of certain novel features of construction, combination and arrangement of parts, as will be more fully described and particularly pointed out in the 45 appended claims.

In the accompanying drawings, Figure 1 is a vertical section of our improved flushing valve mechanism showing the separate valves in a closed position; Fig. 2 is a similar view showing the valves in an open position; Fig. 3 is a horizontal section taken on line 3—3 of Fig. 1.

Corresponding and similar parts are indicated in all the views of the drawings and 55 in the following description by similar reference characters.

In the drawings the numeral 1 designates a pressure tank which is connected to an angularly formed conduit 2 by a union 3. The conduit 2 extends in a vertical plane from the tank 1 with which it communicates by a passage way 4 and is bent at right angles to itself at 5 and again bent at right angles to itself downwardly at 6 and communicates at its lower end 7 with a flushing pipe. 60

The angularly formed conduit 2 is formed with ports 8 and 9, which connect the chamber 10 of said conduit with the chamber 11 communicating with the tank 1. The ports 8 and 9 are arranged to be normally closed 70 by a vertical slide valve 12, which is formed with a depending stem 13, which stem engages a guide arm 14 formed on the inner wall of the conduit 2. The slide valve 12 extends upwardly in the conduit 2 so that the upper portion of said valve normally closes the upper end of the ports 8 and 9 and is connected at its lower end by the stem 13 to a lever 15 which is pivoted to the walls of said conduit and extends longitudinally within the horizontal section thereof. 75

The slide valve 12 is formed with transverse ports 16 and 17; and said valve is preferably formed hollow and the ports 16 are positioned or formed in the lower part 85 of the valve 12 and the ports 17 are formed in the upper part of said valve. The ports 17 are normally closed by an auxiliary valve 18 which slidably extends downwardly through the valve 12 in which it is guided 90 by a spider 19. The lever 15 connects with a gravity ball valve 20 which is normally seated in the valve seat 21 formed in the lower end of the conduit 2 and directly above the opening 7. 95

The conduit 2 is provided with a three-way valve 22 which is formed with an operating handle 23 and said valve is arranged to close a port 24 communicating with chamber 10 and a second port 25 communicating 100 with the flushing pipe. A supply pipe 26 communicates with the casing 27 of the three-way valve 22 and normally exerts pressure in chamber 10. When the three-way valve 22 is in the position indicated in Fig. 1, valve 20 will be held to its seat and valve 12 will be held upwardly across the ports 8 and 9. When the slide valve 22 is turned to the position indicated in Fig. 2, the pressure in chamber 10 will be reduced and 105 water will flow from said chamber by ports 24 and 25 to the flushing pipe by opening 7. 110

This discharge of the water from chamber 10 will relieve the pressure in said chamber and permit the pressure in tank 1 to operate the valves 12 and 20 and thereby open ports 8 and 9. When ports 8 and 9 are thus opened, the water in tank 1 will flow through opening 4 into chamber 11, pass through ports 8 and 9 into the chamber 10, cross to valve seat 21 and empty by means of openings 7 into the flushing pipe.

The slide valve 23 is arranged to be controlled by a spring 28 or an equivalent arrangement, and the valve 20 will be held away from the seat so long as the pressure of the water in chamber 11 and tank 1 exceeds the weight of said valve and, when the weight of the valve 20 more than balances the weight of the water in chamber 11 and tank 1, it will fall to its seat 21. When the valve 20 falls to its seat, the water from the supply pipe 26 will pass upwardly through port 24 into chamber 10, fill said chamber and pass through ports 16 and 17 into the slide valve 12 and fill the chamber 11 and the tank 1, thereby lifting valve 18 from its seat on the upper part of valve 12.

It will be seen that the pressure in the chambers 10 and 11 and tank 1 will cooperate with the valve 12 and valve 20 so that the flushing power of the water is not decreased by the operation of said valves. The tank 1 may be a pressure tank formed with a cover or be an open tank of the conventional kind. It will also be seen that the filling of the chambers 10 and 11 and the tank 1 does not tend to lift the valve 20 from its seat or to detrimentally affect the operation of slide valve 12 with the result that the pressure of the filling water will have the opposite effect it usually has on the closing of the controlling valve.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined in the appended claims.

We claim as our invention:—

1. Means for holding a quantity of water comprising a pressure tank, an angularly formed conduit connected with the pressure tank, said conduit being formed with ports communicating with a chamber in said conduit and said tank, a valve for controlling said ports and a valve coacting with the first mentioned valve for controlling the discharge of water from the conduit.

2. A flushing valve mechanism comprising a pressure tank, a conduit communicating with the pressure tank, a slide valve for con-

trolling the passage of water from the tank to the conduit, a second valve coacting with the first mentioned valve and means for causing the pressure in a supply pipe to hold said valves to their normal positions.

3. A flushing valve mechanism comprising a pressure tank, a conduit connected with the pressure tank, a plurality of chambers, a slide valve dividing the chambers, a second valve coacting with the slide valve, and means for causing the valves to occupy their normal positions by the pressure of water from a supply pipe.

4. A flushing valve mechanism comprising a pressure tank, a compartment communicating with said tank, a slide valve controlling the compartment, a lever connected with the slide valve, a ball valve connected with the lever, and means for utilizing water pressure for causing the valves to occupy their normal positions comprising a three-way valve connected to the conduit.

5. A flushing valve mechanism comprising a pressure tank, a conduit connected with the pressure tank and communicating therewith, a plurality of chambers, a valve for controlling the passage of water from the pressure tank through said chambers, a lever connected to the valve pivotally secured to the conduit, a ball valve secured to one end of the lever, means for controlling the entrance of water into the chambers and the pressure tank, and means for guiding the movement of the first mentioned valve.

6. A flushing valve mechanism comprising a pressure tank, an angularly formed conduit connected to and communicating with the pressure tank, a plurality of chambers one of which communicates with the pressure tank, a vertically movable valve for controlling the passage of water from one chamber into the other, a ball valve coacting with the first mentioned valve, means for guiding the first mentioned valve and a three-way valve for controlling the entrance of water into the chambers.

7. A pressure tank, a conduit connected with the pressure tank, a plurality of ports formed in the conduit, a valve slidable across said ports and arranged to normally close the same, said valve being formed with a plurality of transverse ports, an auxiliary valve for controlling said ports, a lever connected to said slidable valve, means for guiding said valve, a ball valve connected to said lever and a three-way valve for controlling the entrance of water into the conduit and the pressure tank.

8. A flushing valve mechanism comprising a pressure tank, a plurality of coacting valves for controlling the passage of water from the pressure tank, one of said valves being formed with transverse ports and provided with an auxiliary valve for controlling said ports.

9. A flushing valve mechanism comprising a pressure tank, an angularly formed conduit connected with the pressure tank, a plurality of chambers, ports for connecting the chambers, a slide valve arranged to normally control the ports formed with transverse ports and a depending stem, an arm secured interiorly of the conduit for guiding the movement of the valve, a lever connected to the slide valve and pivoted on the conduit, a ball valve connected to the lever and arranged to normally close the lower end of the conduit, a three-way valve having connections with the supply pipe, and means for retaining said slide valve in its normal position.

10. A flushing valve mechanism comprising water receiving means, an angularly formed conduit having a chamber formed

therein, coacting valves movably disposed 20 within the conduit for controlling said chamber, said conduit being formed with ports for connecting said chamber to a flushing pipe, means for controlling said ports whereby the pressure in said chamber is reduced and the pressure of the pressure tank operates the valves, and means for controlling the flow of water into said conduit and into the pressure tank independently of said valves. 25

In testimony whereof we have hereunto set our hands in presence of two subscribing witnesses.
